CAN TURNING MACHINE

Ira H. Kendall, Potsdam, N. Y., assignor to
Genevieve A. Kendall, Potsdam, N. Y.

Application May 13, 1935, Serial No. 21,176

11 Claims. (Cl. 214—1)

My invention relates to a machine for cleansing receptacles and the covers thereof, and more especially milk cans and covers for said cans.

One of the objects of the invention is to provide improved mechanism for reversing the cans from an inverted position to an upright position entirely by mechanical means, and maintaining a proper relation between a can and its cover, so that the cover can be applied to the can at the delivery end of the machine.

Another object of the invention is to provide mechanism for moving the cans from station to station so that the cans are properly located at the successive stations.

15 The invention will be best understood by reference to the accompanying drawings, forming a part of this specification.

20 Figs. 1 and 1a are side elevations of a single line straight line washer, showing the general design of the machine and how some of the more important members are assembled.

25 Fig. 2 is a side elevation showing the means for producing the compounding movement for indexing the can into the inverter, the length of this last compounding movement being greater than the distance between the stations of the machine which are anterior the inverter.

Fig. 3 is a plan view of Fig. 2.

Fig. 4 is a side elevation of the can inverter.

30 Fig. 5 is an end elevation of the can inverter.

Fig. 6 is a plan view of the can inverter.

Fig. 7 is a side elevation of the can inverter and of the gear train which produces the different movements of the indexing mechanism and which 35 also produces the intermittent rotation of the can inverter. This figure also shows the means for applying the power of the gear train and how the motor is mounted so that said motor is caused to rock backward if the normal operation 40 of the machine is obstructed, in order to disconnect the motor power from the gear train.

Fig. 8 is an end elevation of Fig. 7.

Fig. 9 is an end elevation showing the means for mounting the motor so as to enable it to rock 45 backwards.

The machine has a main frame to which the other parts are connected. Said main frame comprises steel channel-irons F.

50 The mechanism for indexing or feeding the cans in successive intermittent strokes, from station to station of the machine, and finally into the inverter, is generally shown.

As shown in Fig. 1a, the reciprocating movement of the can indexing-mechanism is produced by the rotation of gear 81, having the

crank pin 129 mounted in a boss thereof. T-bars 95 have depending arms 82, which are connected to a cross-pin 79 which passes through a bearing of pitman 78, so that pitman 78 can turn relative to cross pin 79. Hence a single pitman 78 moves 5 the T-bars 95 back and forth in unison. This pitman 78 is connected to crank pin 129.

In moving the can from position K (see Fig. 2), into the can inverter, as designated by position D, the can has a greater distance of travel B 10 than in its previous intermittent movements from station to station. The length of each said previous movement is designated by A. This longer final feeding movement is secured by compounding the movement of the last pair of indexing fingers 91 (see Fig. 3), this being desirable 15 so that the inverter bars 104 (see Fig. 2), will not contact with the milk can while it is in position K and while the inverter is being turned.

This compounding movement is accomplished 20 as follows:

Can indexing fingers 91 (see Figs. 2 and 3) are pivoted by pins 112 to slidable bars 93. Said slidable bars 93 are slidably mounted in slide bearings 111, said bearings 111 being mounted on 25 the T-bars 95.

Pitman members 89 are pivotally connected to the respective slidable bars 93 at 90, and each said pitman 89 is pivoted to a lever 83 at 85. Said levers 83 are pivoted to a frame member F 30 at 84. The levers 83 are caused to rock forward and backward by links 87, which are pivotally connected to the respective depending arms 82 of T-bars 95 at 88, and each link 87 is pivotally connected to a lever 83 at 86. The slide bars 93 are 35 thus actuated in unison. As shown in Figs. 1 and 2 the cans are fed into the machine at the left-hand end of Fig. 1.

Since each depending arm 82 is rigidly connected to and has the same movement as its T-bar 40 95, it is clear that each lever 83 at its pivot point 86, will have practically the same stroke as the respective depending arm 82. However, pivot point 85 will have a longer stroke than point 86, since 95 is at a greater distance than 86 from 45 pivot 84, and consequently this longer stroke will be transmitted to the slide bars 93 and the supplemental indexing fingers 91 which are mounted on said slide bars 93.

The slide bars 93 have the full stroke of the 50 T-bars 95, plus the extra stroke of pitman 89 over pitman 87.

The outer ends of fingers 91 carry pins 114.

At about the end of the forward stroke of the fingers 91, pins 114 will contact with the heads 55:

of adjustable bolts 92', which are connected to the frame of the machine, so that the fingers 91 will assume an inoperative position. Near the end of the backward stroke of indexing fingers 5 91, the pins 114 (see Fig. 3) will contact with the heads of adjustable bolts 92 which are connected to the frame of the machine, thus causing the fingers 91 to rotate on their pivot pins 112, and the fingers will then be turned into the operative position illustrated in Fig. 3. While the cans are being moved by the indexing mechanism into the inverter, they slide on stationary bars 94, which are connected to the frame of the machine.

15 The can is indexed into the inverter by the forward movement of the can indexing mechanism, and during the return stroke of the can indexing mechanism, the inverter will make one half of a revolution, thus inverting the can and depositing 20 same on stationary can trackbars 115 (see Fig. 2). The tops of bars 115 are lower than the tops of bars 94, but substantially flush with the inverter bars 104, so the can, when inverted to position E, will rest on can track bars 115 and inverter bars 104. Can ejector members 137 are connected to and they move in unison with slide bars 93, so that upon the next forward movement of bars 93, the members 137 will engage the inverted can and move it out of the outlet side 30 of the inverter, at the same time that a can is being indexed into the inlet side of the inverter by fingers 91. Said can ejector members 137 are located above the bottom bars 104 of the inverter. The ejector members 137 are connected to rods 35 138, which are connected to bars 93, and the rods 138 slide in bearings 139.

The intermittent turning of the can inverter is produced by a pair of intermittent gears forming part of the gear train shown in Figs. 7 40 and 8, this train of gears producing the reciprocating movement of the can indexing mechanism and cover indexing mechanism as well as the turning of the can inverter in a single direction.

This improved can inverter is the first which 45 operates wholly by positive mechanism, thus eliminating the use of the force of gravity, thus providing a positive and accurate method of inverting a can which is of great value, as it is imperative that the inverting of the cans be accomplished in a definite and precise manner, in order to prevent cans from becoming jammed in the machine. Likewise, it is the first inverter which is turned in a single direction, instead of being rocked.

55 The train of gears (Figs. 7 and 8) functions as follows:

Drive motor 123 turns spur gear 122 by any suitable gearing. Spur gear 122 continuously turns a large spur gear 119 which is keyed to shaft 126.

Keyed to shaft 126 is a driving intermittent or mutilated gear 121, having teeth 121a on one half its circumference only, the other half being provided with a shoe 120. The periphery of said shoe 120 is circular and concentric with shaft 126, save that the ends of said shoe 120 are rounded. Said shoe 120 has a periphery of 180°. The radius of the periphery of shoe 120 exceeds the pitch radius of gear teeth 121a of gear 121.

70 Driven gear 117 has teeth over its complete circumference and the same number of teeth as gear 121. Said gears 117 and 121 mesh. Gear 117 has shoe 118 connected thereto, and said shoe has a concave periphery, which corresponds to the convex periphery of shoe 120.

When gear 121 makes one complete revolution, gear 117 will make one complete revolution, but gear 117 makes its complete revolution while gear 121 is turning 180°.

The peripheries of the shoes 118 and 120 are 5 shaped to permit the gear 117 to make a complete revolution, while the gear 121 makes a half revolution. The shoes 118 and 120 then reach the respective positions which are shown in Fig. 7, so that as the teeth 121a go out of mesh with 10 the teeth of the gear 117, the shoe 120 restrains the gear 117 against further movement, until the teeth 121a again mesh with the teeth of gear 117.

The gears 122 and 119 can have different relative diameters, depending upon the speed with 15 which the machine is driven. For example, in Fig. 1a the gear 122 is represented as having a larger diameter than in Fig. 7.

Referring to Fig. 7, the gear 122 turns in the clockwise direction, and the gear 119 turns in the 20 counter-clockwise direction.

The gear 117 meshes with the idler gear 116, and said gear 116 meshes with the gear 110, which is keyed to the shaft 107 of the inverter.

The gears 116 and 110 are of the same diameter, 25 and the gear 117 has one half the diameter of the gear 110 so that there is a gear ratio of 1 to 2 between the gear 117 and the gear 110.

The shaft 107 of the inverter is mounted in bearings 109 as shown in Fig. 8. 30

The can inverter is shown in detail in Fig. 1 and Figs. 5-8 inclusive.

Frame 105 and abutment member 20 are fastened to shaft 107. As shown in Fig. 5, the frame 105 has a rectangular shape, having side bars 35 and end bars.

To frame 105 are welded spacers 106 to which are welded four bars 104, as shown in Fig. 5.

Bars 104 are rigidly fastened together by bars 108. The can inverter is assembled in the machine so that its bars 104 are located between the can track bars 94 and 115. When the inverter is in the position shown in Fig. 2, the tops of the bottom pair of bars 104 are flush with the tops of track bars 115, whose tops are lower than the 45 tops of track bars 94.

This arrangement permits the can to enter the inverter on track bars 94 and to leave the inverter on track bars 115. The members 137 provide sufficient indexing movement for the ejected 50 can, in order to provide clearance for bars 104 when the inverter is turned.

The can indexing mechanism is positively operated at all times and it is superior to the pawls which are now commonly used. 55

The can indexing fingers 11 engage the necks of the cans, so there is no reciprocating mechanism beneath the cans.

When a can is introduced into the machine, it is placed in inverted position upon the plate 164. 60 In said position the can is pushed into the machine by means of dog 167, which is pivoted at 168 to an extension of T-bars 95. When a cover 65 Ca is introduced into the machine it is located upon the upper track bars 18, in the position shown at the left-hand side of Fig. 1. The dog 175, pivoted at 177 to a vertical bar 146b, moves the cover into the machine, from its initial position.

The first indexing of a can and cover is produced by dogs 167 and 175, but after said first movement, the cans are indexed from station to station by indexing fingers, as previously explained, while the covers are indexed by cover feeding dogs 10. 70

- Cover feeding dogs 10 are pivoted at 184 to reciprocating longitudinal cover-feeding dog-bar 146. Stops 144 limit the lowest positions of dogs 10 and stops 147 limit their uppermost positions. 5 The stops 144 and 147 are transverse bars, connected to the longitudinal bar 146, which is connected to bar 146a. Bar 146a is connected to bar 146, by vertical bars 146b.

During the forward movement of bar 146 the 10 dogs 10 pivotally attached thereto will engage the covers and index them at one station. The holding dogs 9 which are pivoted at 143 to a stationary frame member, fall behind the covers and prevent their being moved backward upon the 15 return stroke of bars 146 and 146a. When bars 146 and 146a are moved rearwardly, dogs 9 hold the covers against rearward movement, and dogs 10 then rise, slip over the covers, and then fall behind the covers for the next feeding stroke.

- 20 The covers are discharged into a chute 151 down which each cover slides by gravity to the uprighted can on which the cover is retained in a tilted position.

Referring to Fig. 1, a crank 80' having a pin 80 25 is keyed to shaft 126. This is also shown in Fig. 8. Said pin 80 is connected to link 300, which is pivoted at 300a to bell-crank lever 301, pivoted at 302 to the frame of the machine. Bell-crank lever 301 is pivotally connected at 302a to link 303 which is pivotally connected at 304 to a depending arm of cover-indexing bar 146a. Referring to Fig. 1, the pins 80 and 129 are non-aligned, so that when a can and cover are introduced into the machine, said can and cover are 35 not indexed in unison. The can and cover may each have the same number of intermittent feeding movements through the machine, but the respective feeding strokes are not in unison, and they do not have the same distance of travel. 40 That is, at every movement of a can, it is moved the same distance, save for the compounded movement into the inverter, and possibly the first movement produced by dog 167. Every movement of the cover has the same distance of travel, save when the cover enters the chute 151. However the movement of a cover will be greater than the movement of a can, since the stations for the cover are spaced a greater distance than the stations for the can. The stations for the cover are 45 therefore not superposed relative to the stations for the can.

In the first position of the can within the machine, the milk residue is allowed to drain out of the can. In the next two positions, the can is 55 pre-rinsed, said pre-rinsing being carried on in two stages.

In the first pre-rinsing stage I can use ordinary cold water from a city line or the like. In the second pre-rinsing stage I can use cold water or warm water which may be supplied from the city lines and which may be led through any suitable heater.

The next operation is the first washing stage 60 which is performed by means of water having any suitable cleansing material in solution. The wash water is supplied to the nozzles W under suitable pressure, from the tank T, by means of the pump 47.

The next operation is the "sterile rinse," using 70 sterile rinse water from any suitable source.

The can is then subjected to a series of steaming operations, three steaming stations being illustrated. The steam for said operations is drawn directly from a suitable boiler (not 75 shown).

The can is now dried, two drying stations being shown in this machine.

The can is now indexed into the inverter, and it is then inverted.

Fig. 1 shows the pipe line 700 which supplies 5 wash water to the head 17, which washed the covers.

Fig. 1 also shows a steam ejector 702 which draws water out of a suitable tank and forces the same through the nozzles 703 and 704 for sterile 10 rinsing of the cover. The nozzle 704a supplies the sterile rinse water for rinsing the inside of the can.

Fig. 1 also shows the washing heads 705 for rinsing the outside of the can with sterile water. 15

Fig. 1 also shows washing heads 706 for supplying wash water to the outside of the can.

A safety device is provided for disengaging the gear 122 from the gear 119 and thus stopping the entire drive of the machine if a can becomes 20 jammed or if the operation of the machine requires more than normal power.

Referring to Figs. 7 and 9, the motor 123 is mounted upon a platform 800 and said platform 800 is provided with depending lugs which are 25 connected to a shaft 801a, said shaft 801a being mounted in suitable bearings 810 which are connected to the frame of the machine. The platform 800 also has depending lugs 805' which can abut the frame F, as shown in Fig. 7. The platform 800 is also provided at its rear end with 30 standing lugs 800a to which a lever 805 is pivoted at 805a. Said lever 805 is also pivotally connected at 807 to a lug 806 which is rigidly connected to the frame of the machine. The lever 35 805 is pivotally connected to an upwardly extending link 801a whose length may be adjusted by a turn-buckle device or the like.

The upper end of the link 801 has a hook which passes through the opening in a lever 802. 40 Said lever 802 is pivoted at 803 to the frame of the machine and said lever 802 is provided with an adjustable counterweight 804.

As previously stated, the gear 119 turns in the counterclockwise direction. Hence the reaction 45 of the gear 122 tends to turn the platform 800 in the counterclockwise direction around the shaft 801. This tends to lower the rear end of the platform and to lower lugs 800a, so that lever 805 is turned downwardly on pivot 807, thus 50 pulling down link 801a. The counterweight 804 is adjusted so as to supply the necessary driving force for the machine. If this driving force exceeds the desired limit at any time, the reaction on the gear 122 causes the platform 800 to turn 55 counterclockwise. The bell crank 812 which is connected to limit switch L, which is normally held by spring La in the circuit-closing position shown in Fig. 7, is actuated by rod 812a, the lower end of which is connected to platform 800. 60 The platform then trips the limit switch L, thus opening the circuit of the electric motor 123. The lugs 805' limit the turning of the platform in the clockwise direction. The latch 811a which is pivoted at 811, may also be provided for holding the platform 800, in the position in which the switch remains tripped. The latch 811a as 65 shown in Fig. 7 is in its inoperative position, but when the platform 800 is rocked counterclockwise, the latch 811a will turn by gravity so that its shoulder will engage platform 800 and hold same until the latch is manually released.

I have shown preferred embodiments of the invention, but numerous changes and omissions could be made without departing from its spirit. 70 75

In particular, when I use identification numerals in the claims, this is merely for convenience and the claims are not to be limited to the specific embodiments disclosed as a part identified by a 5 numeral is to be considered as representative of general means for accomplishing the particular function involved.

I claim:

1. In a machine for cleaning receptacles which 10 are open at one end and which are closed at the other end, an inverter, a plurality of equidistant stations located anterior to said inverter, receiving means located after said inverter and located to receive an uprighted receptacle from said inverter, main intermittently operated feeding means operative to feed said receptacles in the inverted position and in equal intermittent strokes from station to station, said inverter being turnably mounted, turning mechanism op- 15 erative to turn said inverter intermittently through an arc of substantially 180° and always in the same direction and away from said feeding means towards said receiving means, first additional intermittently operated feeding means 20 operative to feed the receptacle from the station directly anterior to said inverter into said inverter and in a stroke longer than said intermittent strokes, second additional intermittently operated feeding means for feeding the uprighted 25 receptacle from the inverter to the receiving means after the inverter has been operated to move the receptacle towards said receiving means, said first and second additional feeding means and said turning mechanism being timed in operation so as to feed the inverted receptacle into the inverter while the inverter is stationary, then to operate the inverter while the receptacles are maintained stationary anterior to the inverter and then simultaneously to feed an inverted re- 30 ceptacle into the inverter and to move the up- righted receptacle out of the inverter.

2. In a machine for cleaning receptacles which are open at one end and which are closed at the other end, an inverter, a plurality of equidistant stations located anterior to said inverter, receiving means located after said inverter and located to receive an uprighted receptacle from said inverter, main intermittently operated feeding means operative intermittently to feed said receptacles in the inverted position and in equal intermittent strokes from station to station, said inverter being turnably mounted, turning mechanism operative to turn said inverter intermittently through an arc of substantially 180° and always in the same direction and away from said feeding means towards said receiving means, first additional intermittently operated feeding means operative to feed the receptacle from the station directly anterior to said inverter into said inverter and in a stroke longer than said intermittent strokes, second additional intermittently operating feeding means for feeding the uprighted receptacle from the inverter to the receiving means, said first and second additional feeding means and turning mechanism being timed in operation so as to feed the inverted receptacle into the inverter while the inverter is stationary, then to operate the inverter while the receptacles are maintained stationary anterior to the inverter and then simultaneously to feed an inverted receptacle into the inverter and to move the uprighted receptacle out of the inverter, the width of the inverter being substantially equal to the width of two receptacles.

3. In a machine for handling receptacles, de-

livery means located anterior to the inverter for delivering receptacles thereto, an inverter, receiving means located to receive receptacles from the inverter, mechanism operative to turn said inverter intermittently through an arc of 180° and always in the same direction and away from the delivery means towards the receiving means, said inverter having an inlet end and an outlet end in each position of rest thereof, said inlet end being aligned with delivery means, said outlet end being aligned with said receiving means in the position of rest of the inverter, intermittently operated feeding mechanism for feeding receptacles into the inlet end of the inverter while it is at rest, intermittent feeding mechanism for discharging receptacles from the outlet end of the inverter.

4. In a machine for handling receptacles, de- 10 livery means located anterior to the inverter for delivering receptacles thereto, receiving means located to receive receptacles from the inverter, an inverter, mechanism operative to turn said inverter intermittently through an arc of 180° and always in the same direction and away from the delivery means to the receiving means, said inverter having an inlet end and an outlet end in each position of rest thereof, said inlet end being aligned with said delivery means and said outlet end being aligned with said receiving means in the position of rest of the inverter, intermittently 15 operated feeding mechanism for feeding receptacles into the inlet end of the inverter while it is at rest, intermittently operated mechanism for discharging receptacles from the outlet end of the inverter, said delivery means and said receiving means being located to support the receptacles at substantially the same level as the bottom of the receptacle when it is located in the in- 20 verter, in the position of rest of the inverter.

5. In a machine for handling receptacles, an inverter mounted upon a shaft, and gear means adapted to turn said shaft intermittently in the same direction through an arc of 180° , said gear means including a first gear and a second gear meshing with the first gear, the first gear having gear teeth around its entire circumference, the second gear 25 **121** having the same number of teeth as the first gear around half the circumference of the second gear.

6. In a machine for handling receptacles, an inverter mounted upon a shaft, and gear means adapted to turn said shaft intermittently in the same direction through an arc of 180° , said gear means including a first gear and a second gear meshing with the first gear, the first gear having gear teeth around its entire circumference, the second gear having the same number of teeth as the gear around half the circumference of the second gear, the shafts of the gears having co- 30 operating shoe means for holding the first gear stationary when it is out of mesh with the second gear.

7. A machine for cleansing receptacles, comprising an inverter, said inverter being mounted to turn about a horizontal axis, delivery means located anterior to the inverter for delivering receptacles thereto, receiving means located to receive the receptacles from the inverter, turning mechanism adapted to turn said inverter intermittently and always in the same direction and away from the delivery means towards the receiving means and through an arc of substantially 180° , said inverter having an inlet end and an outlet end which are respectively in registration with said feeding means and said receiving 35 means.

means when the inverter is at rest, the width of the inverter being sufficient to accommodate two receptacles, discharge mechanism adapted to discharge the receptacle from the inverter to the receiving means, said feeding means and said discharge mechanism being connected and being operated in unison so that a receptacle is pushed onto the inverter at its inlet end and a receptacle is discharged from the inverter at its outlet end at

10 the same time.

8. In a can washing machine having a runway along which the cans are advanced in an inverted position, an inverter for righting said cans, said inverter having a plurality of can holders, means for rotating said inverter to move each of said holders in succession first to a position to receive a can from said runway and thereafter to a position at which the can is discharged in an upright position and means upon which the righted can is deposited, said first named means being operative to arrest the movement of said inverter as the cans are delivered to and discharged from said holders.

9. In a can washing machine having a runway along which the cans are advanced in an inverted position, an inverter for righting said cans, said inverter having a plurality of can holders, means for rotating said inverter to move each of said holders in succession first to a position to receive a can from said runway and thereafter to a position at which the can is discharged, a support upon which the righted can is deposited

and means for moving said can along said support, said first named means being operative upon the discharge of a can from one of said holders to further rotate said inverter in the same direction to move a second of said holders to a position to receive a can from said runway.

10. In a can washing machine having a runway along which the cans are advanced in an inverted position, an inverter for righting said cans, a support upon which the righted cans are deposited said inverter having an opposed pair of can holders, each of which has one position in which a can is received from said runway and a second position in which the can is discharged upon said support, means for moving the righted cans along 15 said support and means operative on the movement of a can holder to a can receiving position to cause an operation of said can moving means.

11. In a can washing machine having a runway along which the cans are advanced in an inverted position, an inverter for righting said cans, a support upon which the righted cans are deposited, said inverter having an opposed pair of can holders, each of which has one position in which a can is received from said runway and a second position in which the can is discharged upon said support and means operative on the movement of one of the can holders to a can receiving position to move the can previously discharged from the other of said can holders along 30 said support.

IRA H. KENDALL.
